STEAM BOILER OF THE FLASH TYPE

Howard Bidwell, Amherst, Mass., assignor of
one-half to Linus H. Jones, Amherst, Mass.

Application July 7, 1930, Serial No. 465,849

12 Claims. (Cl. 219—38)

This invention relates to improvements in the method of maintaining a more consistent and uniform water level in steam boilers, and apparatus for heating and operated by electricity.

5 An object of the invention is to provide an apparatus for reducing the change in water level in steam boilers and quickly heating the same. Heretofore, so far as I am aware, it has not been the practice to provide a steam generating unit 10 with a supplemental reservoir for building up the required water level and steam pressure.

Broadly, my invention comprises an electric boiler that is especially applicable to such process work where it is desirable to obtain steam pressure immediately, when high pressure steam cannot be economically or conveniently furnished, particularly, during the non-heating months. The original installations of this type of boiler were in connection with sterilizers, for example, 20 a necessary equipment of biological laboratories and hospitals. However, the apparatus is of such design and flexibility that it can be adapted to a great variety of uses, particularly, in the industrial field. Such data and descriptions recorded 25 in this paper were obtained from experiments conducted by applying steam from this type of electric boiler to a steam sterilizer.

The sterilization of media on which is cultivated parasites of animals, man and plants, is not a rule of thumb procedure. The constituents of the media, particularly sugars, may break down if heat is applied beyond a certain period of time. It is very desirable to obtain a sterilizing pressure (fifteen pounds) in the shortest 30 possible time and to maintain it no longer than between fifteen and twenty minutes. Frequently there is much material to be sterilized and the time element in non-productive work on the part of the attendant and the sterilizer becomes a 35 costly factor. It was just this combination of conditions, plus the lack of direct high pressure steam that prompted the construction of the electric boiler. A supplemental boiler is provided for reducing the change in water level in the small 40 boiler. The capacity of this boiler is very nearly equal to the volume of water that is converted into steam, when the valve is opened in the stem pipe which connects the small steam boiler, on an autoclave for example. The water supplied 45 by the small boiler is therefore a minimum and the change in water level is reduced. The supplemental boiler is provided with a pipe connection, both above and below the water lines of the small 50 boiler. This supplemental boiler is so located 55 with reference to the small main boiler that its

upper and lower water surface is located on a level with the upper and lower water levels in the small boiler, as determined by the water level of the small boiler before and after the valve is opened to an autoclave, or other steam receiving receptacle. One of the purposes of this supplemental boiler arrangement is to conserve the heat required to raise the water in the small boiler to the required pressure and temperature, before the valve is opened. When the valve is opened 10 the water in the supplemental boiler will automatically flow into the small main boiler to replace the greater portion of the water withdrawn in the form of steam and to thereby reduce the change in water level in the small main boiler. 15 It is to be understood that most of the steam which passes from the small main boiler into the autoclave is condensed and is then returned to the boiler and that the portion of the steam which is lost and does not so return is so small that it 20 will be only after several operations of the autoclave that it will be necessary to add water from some source of supply to replace that so lost. Such make-up water as may be required from time to time can be supplied by opening the valve 25 15 and permitting water to flow from some outside source through the pipe 14 into the boiler 1. The heating unit in the boiler is equipped with an independent circuit closing device which operates at constant pressure and temperature, ad- 30 justed for a definite pressure.

Briefly and specifically stated, my improvement comprises the following:

First, a small cylindrically shaped steam boiler of such shape and dimensions that the diameter 35 is only sufficiently large in order to allow, in a practical manner, the insertion of a standard or other water immersion electric heating element (the size or heat generating capacity of the heating element, as well as the boiler, being deter- 40 mined by the steaming requirements that are placed on the boiler), and, to be of only sufficient length or height as to allow, with reasonable steam space, only sufficient water capacity between allowable high water level and allowable 45 low water level; such volume of water as that required with reasonable margin for safety to fill the autoclave, oven, or other pressure vessel used in conjunction with steam of the required pressure or temperature for sterilizing, or other 50 industrial purposes.

Second, employing electric control, automatic or manual, whereby a higher pressure may be carried, maintained or built up in the boiler than that at which the autoclave, or other apparatus 55

in question, is being normally operated, in order that when the autoclave is closed, and with the charge therein to be sterilized and ready for the admission of steam, the required pressure and temperature on the autoclave or vessel may be available in the minimum space of time, due to the heat energy contained in the water in the small boiler under a higher pressure and temperature than that required in the autoclave and with such pressures and manipulation that when the pressure of the boiler and autoclave are equalized, the pressure required on the autoclave or vessel is available, without delay.

The principle underlying the efficiency of this apparatus may be briefly stated as follows:

The electric boiler is of small water capacity, but is constructed to carry a high steam pressure. When the charge has been placed in the sterilizer and all is in readiness for the admission of steam, the required pressure and temperature on the sterilizer may be available in a minimum space of time, due to the heat energy contained in the water in the small boiler under a higher pressure than that required in the sterilizer and with such pressure and manipulation that when the pressure of the boiler and sterilizer are equalized, the pressure required on the sterilizer is available without delay. An automatic pressure control switch will maintain the required sterilizing pressure for whatever period is necessary.

When successive charges are to be sterilized, the second charge goes into the autoclave while the whole system is hot. During the interval of cooling down the first charge so that it can be removed, another high pressure of 90 pounds is being built up from the 15 pounds in the electric boiler. The figures have been obtained which showed that it took eight minutes with an energy consumption of 1.1 kilowatt-hours. During this interval of eight minutes, the first charge was removed and a new charge of twelve liters in two-liter flasks was placed within the sterilizer. The temperature of this water was 54° F. The total energy consumption from the time the electric boiler was shut off from the first charge to the time a sterilizing pressure was obtained on the second charge was 1.6 kilowatt-hours. This energy was consumed in building up a pressure from 15 to 90 pounds, in clearing the sterilizer of air, and raising the pressure within the sterilizer from 0 to 15 pounds.

From these figures, one can easily estimate the cost of energy used in accomplishing this type of work. Other advantages, not discussed here, include the great rapidity in obtaining required pressures, the ease of maintaining a reserve supply of steam that can be quickly applied and a greater efficiency of labor on the part of the attendant. The installation from which the above data was obtained has increased the work done by this sterilizer by 50 per cent and moreover has given an ease and speed of manipulation that has far exceeded expectations. In addition, it has removed the fear of breaking down costly media that frequently occurs, when it takes fifteen or more minutes to bring the sterilizer to the required temperature. This practical apparatus has all the advantages of direct high pressure steam facilities and in fact, it is such, but the steam is produced in an exact and economical manner for the particular sterilizer to which the electric boiler is attached. The opportunities to apply this apparatus in industry are many, especially in processes that require

small amounts of steam for short intervals of time.

Referring to the drawing:

Fig. 1 illustrates the steam boiler with the small auxiliary water boiler and electrical connections to the source of electrical energy, and

Fig. 2 is a sectional view of Fig. 1 through the axis of the boiler, an enlarged sectional detail view of the small boiler showing the electric heating unit therein and the small supplemental boiler which is connected to the small main boiler.

Referring to the drawing in detail:

1 designates the small steam boiler having the lagging covering 2, as shown in Fig. 2 with the 15 electric heating coils or unit 3 therein which closely fits the interior diameter of the boiler. This unit is secured in place by means of the threaded openings 4 in its lower end, as shown. 5 indicates a steam pipe which is connected to 20 the upper end of the small boiler 1 by means of the threaded opening 6, and 7 is a shut-off valve in the pipe 5. The other, or upper end of the steam pipe is understood as being connected to and has communication with an autoclave, 25 or other steam receiving receptacle, as shown in dotted lines at 8. 9 designates the small auxiliary water supply boiler or auxiliary water chamber, 10 a pipe connecting the bottom of the auxiliary boiler with the bottom of the main boiler, 30 at 11. 12 is a draw-off pipe having the valve 13. 14 is a main water supply pipe having a shut-off 15 therein. 16 is a pipe connected to the upper side of the small water boiler 9. 17 is a steam pressure gage connected to the pipe 35 18. 19 designates an electric thermostat which is electrically connected to the switch 20 in the main circuit wires 21, which supplies current to the heating units 3. 22 is a baffle plate.

The high water level is indicated at 23, which 40 is the same level as that in the small boiler 9 at 24. The low water level is indicated at 25 and the corresponding low water level at 26.

27 is a transformer, 28 the main power lines having a switch 29 therein. 30 is an electro- 45 magnetic switch in the circuit wires 31 and 32 to the thermostat 19. 33 and 34 are the wires connected to the primary windings of the transformer 27. 35 are the circuit wires of the three phase system connected to the heating units 3. 50 36 are the supporting legs.

The short pipe 37 connects the small auxiliary water boiler 9 to the main boiler 1.

When the apparatus is started, the water level is at the lines 23 and 24, and the boiler 1 is 55 completely filled, as shown. As heat is applied to the boiler 1, heat is transmitted to the water in the boiler 9 by the pipe 37. When the valve 7 is opened and some of the water in the boiler 1 at high temperature and pressure, as 60 lbs. 60 is converted into steam, water will then flow from boiler 9 into boiler 1 through the pipe 10. This will operate to restore the water level in the boiler 1. In other words, the water from boiler 9 serves to reduce the change in water level in 65 the boiler 1, when the valve 7 is opened for sterilization, or other commercial purposes, as cleaning or steaming garments.

The operation may be described as follows: it being understood that only a sufficient quantity 70 of water is placed in the main small boiler 1, whereby a reduction in water level is sufficient to provide a volume of steam that will fill the autoclave, or other receptacle 8, at a definite temperature and pressure for sterilization, or other pur- 75

poses, when the valve 7 in the pipe 5 is opened. In other words, the specific volume of steam at a definite pressure and temperature in the receptacle 8 is determined by the quantity of water in the small boiler 1, when it is at a definite pressure and temperature, before the valve 7 is opened, whereby the small volume of water, or some of it in the boiler 1 is immediately converted into steam, when this valve is opened in order to produce the required temperature and pressure in the receptacle 8 for sterilization, or other purposes.

Assume that the water in the small boiler at starting is at the high water line level, indicated at 23. The main switch 29 and the electromagnetic switch 20 are closed and an electric current is flowing to the heating units 3 by means of the wires 21 and 35. The steam generated will rise in pressure until the gage 17 indicates, say 60 lbs., at which pressure the pressure control contacts 19 would open, if set for this pressure. The manual switch 29 is understood as being closed. As soon as the contact at 19 opens, a current ceases to flow through the coil 30, which opens the electromagnetic switch 20 and cuts off the current to the heating units 3. The current in this circuit operates the part 30¹ and opens the circuit in the wires 35 to the heating unit. The operator now opens the valve 7 and allows steam at 60 pounds to enter the receptacle 8. By reason of a sudden release of the pressure, a sufficient quantity of water in the boiler 1 is converted into steam and passes into the receptacle at 15 lbs., or the desired sterilizing pressure, which is the usual sterilizing pressure. The low water level is now indicated at 25, when the water in the boiler 9 would be about one-half used.

In order to indicate the sterilizing temperature at 15 lbs. pressure, the steam gage 17 is employed. The low pressure control contact 19 will open at 15 lbs., or at the desired pressure. When the pressure reaches 15 lbs. pressure, the coil 30 again operates to open the electromagnetic switch.

It will be seen that the boiler 1 serves to maintain the water level nearly constant at all times, and also the steam space.

What I claim is:

1. In combination with a steam receiving receptacle, as an autoclave, a steam boiler of small capacity, means for heating the same, means for automatically supplying water to the small steam boiler when steam is admitted into the autoclave whereby the change in the water level in the small steam boiler is reduced, said means comprising a supplementary boiler having its upper, inner surface located in substantially the same horizontal plane as the high water level of the small steam boiler and having its lower inner surface located in substantially the same horizontal plane as the low water level of the small steam boiler, the supplementary boiler having pipe connections to the small steam boiler both above and below the water level in the small steam boiler, and a pipe connection from the small steam boiler to the supplementary boiler midway between the high and low water levels in the small steam boiler.

2. In a main steam boiler, of small water and steam capacity, a supplemental boiler, means for connecting the supplemental boiler to the main boiler, comprising pipe connections at its upper, lower and intermediate points, the water capacity of the supplemental boiler being in addition to and supplementing the amount of water available from the main boiler between high and low water

levels of the main boiler, and means for heating the water in the main steam boiler comprising electric units which substantially fill the same up to the low water level.

3. In combination, a boiler adapted to raise the temperature of an autoclave or other receptacle to its operating temperature within a short period of time, said boiler being adapted to be filled with water when the autoclave is not in operation, means for heating the water in said boiler to a temperature and corresponding pressure in excess of that required in the autoclave, means for permitting steam to flow from the boiler into the autoclave to heat said autoclave whereby the pressure and temperature in the boiler is reduced thereby utilizing the latent heat of vaporization of the water and a portion of the water passes from the boiler into the autoclave in the form of steam, an auxiliary water chamber, connections between said boiler and said water chamber providing water circulation therebetween while heating and also providing means for the water to flow from the latter into the former to reduce the change in level of the water in the boiler due to the withdrawal of the portion of said water which passes into the autoclave.

4. In combination with a steam boiler of small steam capacity, an auxiliary water chamber, and permanent connections at two different levels each of which is below the high water level between said chamber and said boiler to provide water circulation therebetween so that the temperature of the water in said chamber will be substantially as high as that of the water in said boiler.

5. In combination with a steam boiler of small steam capacity, an auxiliary water chamber, connections between the top of said chamber and the boiler at a portion thereof above the high water level, a second set of connections between the bottom of said chamber and said boiler at a portion thereof below the low water level, and a third set of connections between said chamber and said boiler substantially midway between the high and low water levels.

6. In combination, a steam boiler having vertical dimensions substantially greater than any of its horizontal dimensions, an auxiliary water chamber having a horizontal dimension substantially greater than any of its vertical dimensions positioned adjacent to said boiler and at the water level thereof, and connections at two different levels each of which is below the high water level between said chamber and said boiler to provide circulation of water therebetween.

7. In combination, a steam boiler of cylindrical form with its axis positioned vertically, an auxiliary reservoir of cylindrical form with its axis positioned horizontally, said reservoir being positioned adjacent to the boiler at the water line thereof, and connections at two different levels each of which is below the high water level between said reservoir and said boiler to provide circulation of water therebetween.

8. Apparatus for supplying steam to an autoclave comprising a lower portion of small size for the reception of electric heating elements and adapted to be filled with water at both high and low water levels, and an upper portion having a horizontal cross-sectional area much larger than said lower portion whereby the change in water level caused by supplying steam to the autoclave is less than with apparatus having the same horizontal cross-sectional area at all levels.

9. In combination with a steam boiler of small steam capacity, an auxiliary water chamber, and connections at two different levels each of which is below the high water level between said boiler and said chamber to provide water circulation therebetween whereby the water in said chamber is maintained at the same temperature as the water in said steam boiler, said connections between said chamber and said boiler also constituting means whereby water flows automatically from said chamber into said boiler when steam is drawn from said boiler.

10. In combination with a steam boiler of small steam capacity, an auxiliary water chamber positioned at the water level of said boiler, and connections to provide water circulation therebetween comprising a passage from said chamber below the high water level and above its lower portion directly to said boiler and another passage from the lower portion of said chamber to the lower portion of said boiler positioned so as not to be directly heated by the boiler.

11. In combination, a steam boiler having a uniform horizontal cross-sectional area through-

out, an electric heating element positioned in said boiler below the low water level thereof so as to be always submerged, and an auxiliary water chamber connected with said boiler and so positioned that its entire water capacity is available before the level of the water is reduced to the top of said heating element.

12. A steam boiler adapted to furnish a predetermined quantity of steam with a minimum change in water level and to provide water submergence for electrical heating elements at all times comprising a compartment for heating elements having a small horizontal cross-sectional area compared with its vertical dimension and a second compartment positioned at a level above the level of the top of said heating elements having a large horizontal cross-sectional area compared with the first-named compartment and a small vertical dimension compared with the first-named compartment and a plurality of connections between said compartments to provide free circulation of water therebetween at temperatures below that necessary to generate steam.

HOWARD BIDWELL.
